UNITED STATES PATENT OFFICE.

WALTER J. AVERY, OF CAMBRIDGE, MASSACHUSETTS.

DESIGN FOR A LAMP-BODY.

52,107.

Specification for Design.

Patented June 18, 1918.

Application filed December 27, 1917. Serial No. 209,183. Term of patent 7 years.

To all whom it may concern:

Be it known that I, WALTER J. AVERY, a citizen of the United States, residing at Cambridge, in the county of Middlesex and State of Massachusetts, have invented a new, original, and ornamental Design for Lamp-Bodies, of which the following is a specification, reference being had to the accompanying drawing, forming part thereof.

The figure is a perspective view of a lamp showing my new design.

I claim:

The ornamental design for a lamp body as shown.

WALTER J. AVERY.

Witnesses:

JOSEPH J. McCARTHY,
JOHN W. MURPHY.
